(57) **CLAIM**

The ornamental design for a front fender for a backhoe loader, as shown and described.

DESCRIPTION

FIG. 1 is a front, side, and top view of a left front fender for a backhoe loader showing one embodiment of the new design.

FIG. 2 is a top plan view of the left front fender for a backhoe loader.

FIG. 3 is a front elevation view of a right front fender showing the same design.

FIG. 4 is a side elevation view of the right front fender.

FIG. 5 is a right-side elevation view showing the placement of the front fenders on the hood of a backhoe loader.

FIG. 6 is a front, side, and top view of the right front fender.

FIG. 7 is a top plan view of the right front fender.

FIG. 8 is a front, inside, and top view of the right front fender.

FIG. 9 is front elevation view of the left front fender; and, FIG. 10 is a front, inside, and top view of the left front fender.

The broken lines show environmental structure and form no part of the claimed design.

1 Claim, 10 Drawing Sheets
